J. H. Richards

UNITED STATES PATENT OFFICE.

GEORGE B. PILKINGTON, OF NEW BRITAIN, CONNECTICUT, ASSIGNOR TO
THE TRAUT & HINE COMPANY, OF SAME PLACE.

SUSPENDER-BUCKLE.

SPECIFICATION forming part of Letters Patent No. 431,992, dated July 8, 1890.

Application filed May 1, 1890. Serial No. 350,230. (No model.)

To all whom it may concern:

Be it known that I, GEORGE B. PILKINGTON, a citizen of the United States, residing at New Britain, in the county of Hartford and State 5 of Connecticut, have invented certain new and useful Improvements in Suspender-Buckles, of which the following is a specification.

This invention relates to buckles for suspenders and to that class of suspender-buckles 10 having "cast-offs," the object being to provide improved means for unhooking the catches thereof, as hereinafter more fully set forth.

In the drawings accompanying and forming a part of this specification, Figure 1 is a front 15 or side view of a buckle embodying my improvements. Fig. 2 is an edge view of the same drawn in projection with Fig. 1. Fig. 3 is a longitudinal section through the middle of the buckle, showing the slide hooked in 20 place and illustrating the construction of the slide-detaching device. Fig. 4 is a view similar to Fig. 3, showing the slide in place, but unhooked.

Similar characters designate like parts in 25 all the figures.

My improved buckle consists of a buckle-plate B, constructed with a slide-receiving box D, any suitable means for attaching the said plate to the usual web of the suspender, 30 and the slide S, fitting said box, in which it is adapted to be locked and unlocked by means of my newly-invented improvements. The means for attaching the plate B to the suspender-web are shown, consisting of the teeth 35 2, formed on said plate, and the lever L, having ears 16, carried by the pivots 4, which are formed on said plate B in a well-known manner. These web-holding devices being old and well known, a more particular description of them or of their mode of operation 40 will be unnecessary. Slide S has the usual loop 6 for attaching the suspender-straps thereto, the plate or slide proper 7, and the spring 8, usually formed integral with the slide part 45 7 by a bend at 9. On the lower end and front

of the box D there is a hook 5, with which the end of the spring 8 engages when the slide is in place, as shown in Fig. 3, thereby securely locking said slide to the buckle-plate. As a means for detaching said spring-catch 8, I 50 form in the front of the box D a push-button N, which is movably supported on the lower end of a spring 10. As shown in Fig. 3, said push-button rests on said spring-catch 8 and projects forward of the box D. When wishing to detach the slide S, the user pushes 55 on said button N, thereby closing down the spring-catch 8 out of engagement with said hook 5, as shown in Fig. 4, thus permitting said slide to be readily withdrawn from said 60 box D with no other resistance than that offered by the friction of said slide between the back-plate 12 and said button N. In constructing buckles having my improvements I form the button N and its supporting-spring 10 integral with the plate B, separating them by cutting the metal of said plate, as indicated by the boundary lines of said spring and push-button, as shown in Fig. 1.

Having thus described my invention, I 70 claim—

1. In a buckle, the combination, with the slide-box having the hook at the lower end thereof, of the slide having the spring engaging said hook, and a push-button movably 75 supported on a yielding arm formed in the front of said box over and bearing on said spring, whereby the spring may be closed for unhooking the slide.

2. In a buckle, the combination, with the 80 buckle-plate having the slide-box D and the hook 5 at the lower end of said box, of the slide S, having the spring 8, whose point engages said hook, and the spring 10, formed in the front of the slide-box and having the 85 push-button at the lower end thereof.

GEORGE B. PILKINGTON.
